INK PAD

Stewart W. Partridge, Grand Island, Nebr.

Application May 25, 1931. Serial No. 539,889

5 Claims. (Cl. 91—54.5)

My present invention has reference to a new and novel construction of ink pads for applying ink to rubber stamps or the like, and has for its primary object the provision of a pad for this purpose 5 of soft non-porous elastic material having one of its faces slitted or otherwise cut to provide the same with wells and a core or plug in each well that will normally close the wells and retain the ink therein, the said plugs being constructed of the same material as the body and yieldable under pressure, and when such pressure is applied the ink from the wells will ooze in small but determined quantities from the wells to the outer face of the pad so that the letters on 10 the stamp can be properly inked in a better, easier, and more expeditious manner than can be accomplished by the ordinary pad construction, and further wherein the ink being retained separately in the several wells will last for a comparatively 15 long length of time far greater than that of the ordinary pads.

A further object is the provision of a pad of this character in which the ink can be inserted in the wells by merely arching the pad to cause the 20 plugs to be projected through the wells and to be wiped by a brush containing a small quantity of ink, such ink being delivered into and sealed in the wells when the pad is permitted to resume its normal substantially rectangular shape.

To the attainment of the foregoing the invention 25 consists in the improvement hereinafter described and definitely claimed.

In the drawing:

Figure 1 is a top plan view of an ink applying 30 pad in accordance with this invention.

Figure 2 is a sectional view approximately on the line 2—2 of Figure 1.

Figure 3 is a sectional view approximately on the line 3—3 of Figure 1.

Figure 4 is a perspective view of a slight modification.

Figure 5 is an inverted plan view thereof.

Figure 6 is a transverse sectional view showing the pad arched for the application of ink thereto.

In the showing of the drawing the pads 1 are of rectangular formation, but obviously the same may be of any shape and thickness. The pad is formed from a rubber composition that renders the same soft and non-porous and likewise renders 45 the same elastic and, therefore, susceptible of expansion and contraction. The elasticity of the pad also serves to hold the same in its normal shape. One face of the pad, at very close intervals, is slitted, cut or otherwise formed with substantially conical portions that afford wells 2, and

between the wells there are reversely arranged conical portions in the nature of cores, but as these cores are designed to seal the wells I will hereinafter refer to the same as plugs. The plugs 60 are indicated by the numeral 3.

To apply ink to the wells, the body 1 is arched as disclosed by Figure 6 of the drawing, and a brush containing a small but sufficient quantity of ink is wiped over the outer and widened ends of the plugs 3. When the body 1, incident to its inherent elasticity is permitted to return to its initial shape the plugs 3 enter the wells 2, delivering ink into the said wells and likewise seal the wells. A slight pressure of the stamp on the pad 65 will compress the plugs and the portions of the body adjacent the plugs. The compressed plugs will force the ink from the wells onto the outer face of the body so that the same is freely delivered onto the stamp.

In Figure 4 the body 1' may have its ends provided with beads 4 to permit of the said body being readily gripped and the body, on its under face, is provided with depressions that afford vacuum cups 5. This will prevent the free sliding of the body 1' on the surface on which it rests and the free sliding of the body 1 is prevented by providing the under face thereof with a fabric or like facing 6.

It is to be understood that the wells may be 75 of any desired shape as may be the plugs that are arranged in and normally close or seal the wells. The ink in the wells is not permitted to flow through the body because of the non-porous nature of the body. The body is soft and yieldable so that only a slight pressure of the stamp 80 thereagainst is required in the inking operation.

The ink in the wells being sealed will last for practically an indefinite period of time and the compression of the plugs and the portions of the body adjacent the closely related wells and plugs 85 will cause a desired quantity of the ink to be forced from the several wells. The pressure of the stamp upon the pad will slightly compress the said pad, causing the openings affording the wells to have their mouth portions spread and thereby enlarged and likewise causing the plugs to be forced into the wells so that the said plugs 90 have a plunger action upon the ink in the well to cause a desired quantity of the said ink (in accordance with the pressure exerted by the stamp on the pad) to flow through the wells onto the outer surface of the pad and thus permit of the inking of the stamp. The wells being sealed by the plugs prevent the liability of the 95 congealing of the ink in the wells and the conse-

100

105

110

quent clogging of the wells is thus effectively prevented. Furthermore, the device can be arranged upside down and the plugs will prevent the ink from flowing through the wells.

5 Having described the invention, I claim:

1. A stamp inking pad comprising a body of soft non-porous and elastic material having closely related ink wells entering from one face thereof, and a plug formed from the body in and sealing each well.

10 2. An inking pad of the type described, comprising a body of soft elastic and non-porous material having one of its faces slotted throughout at close intervals to provide cone-shaped ink wells and cone-shaped plugs in and sealing the wells.

15 3. A stamp inking pad comprising a body of soft non-porous elastic material, having one of its faces provided with closely related series of ink receiving wells, and a plug also of soft non-porous elastic material and having a portion fixed in each of the wells and said plugs nor-

mally sealing the wells, and said wells, when a pressure is exerted against the pad, adapted to have their mouths spread and the outer ends of the plugs likewise spread and forced into the wells to exert a piston action against the ink in 80 the wells.

4. An inking pad of soft elastic non-porous material provided with ink receiving conical wells, and an inverted conical plug also of soft elastic non-porous material in and normally sealing each ink well. 85

5. A stamp inking pad comprising a body of soft non-porous and elastic material having closely related ink wells entering from one face thereof for the major width of said pad, and a 90 plug formed from the body in each well, said plugs normally sealing the wells and designed, when pressure is exerted thereagainst, to assist in spreading the mouths of the wells by entering the said wells and effecting a piston action upon 95 the ink in the wells.
